UNITED STATES PATENT OFFICE.

DICKRAN M. SARKISIAN, OF FOREST HILLS, NEW YORK.

CURTAIN ROD AND BRACKET THEREFOR.

Application filed November 19, 1924. Serial No. 750,744.

To all whom it may concern:

Be it known that I, DICKRAN M. SARKISIAN, a citizen of the United States, and a resident of Forest Hills, county of Queens, 5 State of New York, have invented certain new and useful Improvements in Curtain Rods and Brackets Therefor, of which the following is a specification.

This invention relates to curtain rods and 10 brackets therefor.

An important object of the invention is to provide in a curtain rod and bracket assembly a simplified cooperative combination of elements so related as to effectively retain 15 the rod in position upon the supporting bracket under ordinary conditions but yet permit the rod to be readily detached when so desired.

Other objects and certain advantages of 20 the invention will become apparent from the following description when taken in connection with the accompanying drawings in which—

Figure 1 is a perspective view of the rod 25 and bracket assembly embodying my invention.

Figure 2 is a fragmental plan view of one end of the rod and also one of the supports shown in Figure 1.

Figure 3 is a transverse sectional view 30 taken on line 3—3 of Figure 1.

Figure 4 is a fragmental enlarged plan view of that end of the rod shown in Figure 2.

Figure 5 is a view similar to that of Figure 2 but showing a slightly modified form of rod.

Referring to the drawings, the numeral 5 indicates a curtain rod of the expandible 40 type comprising telescopic members 6 and 7 bent at their respective ends to provide arms 8 and 9. These arms, like the main portions of the sections 6 and 7, are formed from a flat strip of metal which is bent or curved at its longitudinal edges to provide U-shaped flanges 10. These flanges are at the inner or extreme ends of the arms 8 and 9 punched to provide I-shaped openings 14 as shown most clearly in Figure 5, thus forming more or less resilient inwardly projecting wings 15 the purpose of which will hereinafter become more apparent.

As a means for supporting the rod 5 I 45 provide a pair of brackets, each of which is indicated by the numeral 16. These brackets are each formed from a single piece of

metal which is so shaped as to provide a base 17 having an arm or tongue 18 formed integral therewith. The tongues or arms are adapted to enter the openings 14, as most 50 clearly shown in Figure 1, and are provided with lugs or protrusions 19 relatively near their outer ends and their point of connection with their respective bases 17. These lugs or protrusions are preferably formed 55 by indenting the arms at one side and thus causing the metal to project from the other side as shown. When placing the rod upon the fingers 18 on the brackets 16, the wings 15 being more or less resilient will slightly 60 yield and thereby permit the same to pass over the lugs or protrusions 19. Once the wings 15 have passed over these protrusions they, because of their resiliency, will spring 65 back to their respective normal positions, in 70 which case the space afforded between the wings will be slightly less than the over-all thickness of the protrusions plus the tongues from which they are formed. It will be 75 readily appreciated, therefore, that the 80 wings 15, cooperating as they do with the lugs or protrusions 19, so function as to effectively retain the rod in position on the fingers 18 as shown in Figure 1.

By reason of the fact that the members 6 and 7 of the rod 5 are telescopic it follows 85 that the space afforded between the openings 14 of the arm 9 will be slightly greater than the space afforded between the similar openings formed in the arm 8, but I do not propose to employ different spacing between the lugs or protrusions of opposite brackets, although if desired, this practice may be followed in production. If standard spacing 90 between the lugs 19 is adhered to, the space 95 between these lugs should be such that the wings 15 carried by the wider arm will engage both lugs as shown most clearly in Figure 3. The arm 8 being somewhat narrower than the arm 9 and the spacing between the lugs carried by the bracket associated with the arm being the same as the spacing between the lugs of the opposite bracket, it follows that only one pair of 100 wings carried by the arm 8 will function at a time to lock the arm with respect to its associated bracket, although both pairs of wings carried by this arm may be positioned below the respective lug as shown in Figure 105 100. One pair of wings, however, I have 110 found is sufficient to effect the necessary locking and it makes no difference whether

it be the upper pair or the lower pair as will be readily appreciated. The lower pair of wings, when the arm 8 is positioned as shown in Figure 1, will function as a locking means but if it is attempted to remove the arm 8 from the finger 18 the upper pair of wings will then function as a locking means subsequent to the disengagement of the lower pair of wings from the lower lug, thus doubly insuring the retention of the arm 8 upon the finger 18.

Although not shown in the complete assembly of Figure 1 it will be readily appreciated that the brackets 16 may be attached to a window, door or other suitable frame or support shown in Figure 2 and indicated by the numeral 20, suitable opening 21 being provided in each of the brackets for the reception of screws or other fastening means.

Referring to Figure 5 wherein I have shown a slightly modified form of curtain rod it will be noted that the openings 14' adapted for the reception of the fingers 18 are rectangular in shape, no pronounced wing structure being provided. Wings, however, are present and are indicated by the numeral 15'. These wings are more or less resilient, the same as explained in connection with the wings 15, and are so by reason of the fact that the wings 15' are themselves resilient, and the further fact that the opening 14' is slightly less in width than the space afforded between adjacent faces of the flanges 10 around the curve of the U-shaped flange-forming wall of the rod. The wings, employed in connection with the modified form of my invention, are adapted to cooperate with the lugs or protrusions 19 and function in substantially the same manner as explained in connection with the form of my invention shown in Figures 1 to 4 inclusive.

Having thus described certain embodiments of my invention, I claim:

1. The combination with a sheet metal curtain rod having a flange provided with an opening so shaped as to provide a resilient wing projecting into the opening, of a bracket including a finger adapted to enter said opening and a rigid locking device carried by said finger and adapted to cooperate with said wing to retain the rod in position.

2. The combination with a sheet metal curtain rod having a flange provided with an opening so shaped as to provide a resilient wing projecting into the opening, of a bracket including a tongue adapted to enter said opening and having a rigid protrusion adapted to cooperate with said wing to retain said rod in position.

3. The combination with a sheet metal curtain rod having a flange provided with an opening so shaped as to form a pair of resiliently yieldable wings projecting to-

ward each other into the opening, of a curtain bracket having a tongue adapted to enter said opening, and unyielding means on said tongue and adapted to cooperate with said wings to retain said rod in position.

4. The combination with a sheet metal curtain rod having a flange provided with an opening so shaped as to form a pair of resilient wings projecting toward each other into the opening, of a curtain bracket having a tongue adapted to enter said opening and having a rigid protrusion adapted to cooperate with said wings to retain said rod in position.

5. The combination with a sheet metal curtain rod having a pair of flanges provided with openings so shaped as to form resiliently yieldable wings projecting into the openings, of a bracket having a tongue adapted to enter said openings, and unyielding locking means on said tongue and adapted to cooperate with said wings for retaining said rod in position.

6. The combination with a sheet metal curtain rod having a pair of flanges provided with openings so shaped as to form resiliently yieldable wings projecting into the openings, of a sheet metal bracket having a tongue adapted to enter said openings, and unyielding locking means carried by said tongue and adapted to cooperate with said wings for retaining said rod in position, said locking means being in the form of rigid protrusions resulting from the formation of depressions in said tongue.

7. The combination with a sheet metal curtain rod having a pair of flanges provided with I-shaped openings, thereby to form a pair of resiliently yieldable wings carried by said flanges and projecting toward each other into said openings, of a bracket having a tongue adapted to enter said openings, and unyielding locking means on said tongue and adapted to cooperate with said wings to retain said rod in position.

8. The combination with a sheet metal curtain rod having a pair of flanges provided with I-shaped openings, thereby to form a pair of resiliently yieldable wings carried by said flanges and projecting toward each other into said openings, of a sheet metal bracket having a tongue adapted to enter said openings, and unyielding locking means carried by said tongue and adapted to cooperate with said wings to retain said rod in position, said locking means being in the form of rigid lugs or protrusions formed upon one side of said tongue as a result of said tongue having been depressed from its opposite side.

9. In combination, a curtain rod having an end thereof provided with a resiliently expandable opening through it transversely

thereof, and a rod-supporting bracket having a finger to enter said opening and adapted to be resiliently gripped therein to retain the rod on the finger.

5 10. In combination, a curtain rod having an opening transversely through an end thereof, a portion of the rod defining the opening being resiliently yieldable, and a bracket having a finger to pass through said

10 opening and provided with unyielding means to be engaged by said resiliently yieldable rod portion for retaining the rod on the finger.

11. In combination, a curtain rod having an opening transversely through an end thereof, a portion of the rod defining the opening being resiliently yieldable, and a bracket having a finger to pass through said opening and provided with a rigid lug engageable by said resiliently yieldable rod portion for retaining the rod on the finger.

12. In combination, a curtain rod provided with an opening transversely through an end thereof, and a bracket having a finger to pass through said opening, the rod being provided with resiliently yieldable means engageable with the finger to retain the rod thereon.

13. In combination, a curtain rod having an opening transversely through an end thereof and provided with a resiliently yieldable projection, and a bracket having a finger provided with unyielding means with which said projection is yieldingly engageable to retain the rod on the finger.

14. In combination, a rod-supporting bracket having a finger provided with a rigid lug, and a curtain rod having an opening transversely through an end thereof to receive said finger and provided with re-

siliently yieldable means to engage said lug for retaining the rod on the finger.

15. In combination, a rod-supporting bracket having a finger provided with a rigid lug, and a curtain rod having an opening transversely through an end thereof to receive said finger and provided with a resiliently yieldable projection to engage said lug for retaining the rod on the finger.

16. In combination, a sheet metal curtain rod having an elongated opening transversely through an end thereof, the portions of the rod forming the elongated sides of the opening being resiliently yieldable thereby to render the opening resiliently expansible in width, and a bracket having a finger provided with a rigid lug to be engaged by said resiliently yieldable rod portions forming the sides of said expansible opening for thereby retaining the rod on the finger.

17. In combination, a sheet metal curtain rod having at an end thereof a U-shaped flange provided with a longitudinally extending elongated opening and the portions of the rod at the sides of such opening being resiliently yieldable, whereby and because of the U-shape of the flange said opening is resiliently expansible in width, and a sheet metal bracket having a flat finger to pass through said opening and provided on a side thereof with a rigid lug engageable by said resiliently yieldable rod portions forming the sides of said expansible opening for thereby retaining the rod on the finger.

In testimony whereof, I have affixed my signature to this specification.

DICKRAN M. SARKISIAN.
